FIRE CONTROL SYSTEM FOR AIRCRAFT GUNS

Earl W. Chafee, New York, N. Y., assignor to Sperry Gyroscope Company, Inc., Brooklyn, N. Y., a corporation of New York

Application June 3, 1938, Serial No. 211,550

17 Claims.

(Cl. 33—49)

This invention relates to a special case of fire control apparatus adapted for directing gunfire from one airplane at another airplane, such as where a high speed attack plane is trailing a bomber, in which case the attacking plane by its superior speed is enabled to maintain a fairly constant range and fly a course parallel to that of the target thereby maintaining a constant sight angle in azimuth and elevation. However, provision is preferably made in the apparatus to take care of continuous rate of change of angles in both azimuth and elevation. My automatic sight and computer provides a means for sighting and tracking the target, for obtaining the range thereof, and the air speed of the attacking plane, and automatically computing azimuth and elevation deflections therefrom. It further provides means for training the guns from such sight. Preferably the computed deflections are applied in both azimuth and elevation between the line of fire and the line of sight.

In the preferred arrangement, the movement of the control handle at the sight controls the guns instead of the sight, while the calculated deflections are put in between the repeat-back from the guns to the sight, so that the line of sight is thus moved away from its former position. This motion of the telescope is not a sudden motion, but flows in gradually while both telescope and gun are being trained on the target. Therefore the gun is automatically trained and elevated to its correct position for firing by bringing the target into the reticle of the sight.

Other objects of the invention will be apparent from the following description.

Referring to the drawings,

Figs. 1A and 1B are the two halves of a diagram showing my improved sight, range finder and computer.

Fig. 2 is a perspective view of the wind resolving mechanism thereof.

Fig. 3 is a diagram showing the principles of operation of the range finder employed therein.

Figs. 4A and 4B are diagrams illustrating the passage of light rays through a part of the optical system of the range finder.

Fig. 5 is a detail of the mechanism for rotating the line of sight in elevation.

Fig. 6 is a detail of the range computing mechanism.

Fig. 7 is an elevation view of a gun adapted to be aimed by the control means at the sight.

The main control lever for operating the sight is a universally pivoted handle 1, (see Fig. 1B) the angular motion of which may be identical

with the movements of the gun. The motion thereof is transmitted in azimuth and elevation components, the former being transmitted by the rocking of the handle into and out of the plane of the paper, which rotates shaft 2 through a gear sector 3 and pinion 3', shaft 2 connecting with azimuth control 7, the output shaft 2' of which operatively connects with the azimuth drive mechanism of gun 100 (see Fig. 7). Rocking of lever 1 in the plane of the paper moves the rack bar 4 up and down to rotate pinion 5 and shafts 5' and 6, shaft 6 connecting with elevation control 8, the output shaft 6' of which operatively connects with the elevation drive mechanism of the gun. The shafts 2 and 6 do not, of course, actually move the gun directly, but through a servomotor system which for illustration may be similar to the well known Waterbury type of hydraulic transmission, herein represented by the dotted line rectangles 7 and 8. The output shafts 2' and 6' from the azimuth and elevation control devices 7 and 8 position the gun in azimuth and elevation, respectively. Referring specifically to Fig. 7, gun 100 is supported by mount 101 for rotation in elevation about horizontal trunnion 102, this rotation being effected, in the embodiment illustrated, from shaft 6' by means of worm 103 meshing with gear segment 104 carried by the gun. Mount 101 is rotated in azimuth about a vertical axis from shaft 2' by means of worm 106 meshing with worm wheel 105 fastened to or integral with the mount. The azimuth and elevation repeat-back shafts 9 and 10 are connected with the gun and may be driven from shafts 2' and 6', respectively, through gearing as shown. Shafts 9 and 10 have certain corrections applied thereto within the computer and then actually turn the line of sight in azimuth and elevation relatively to the gun by actuating movable parts of a telescope 21—22 of a type known as a panoramic sight.

The line of sight enters the eye-piece 13 and passes horizontally through penta prism 14, and thence vertically through a pair of reversely rotated wedge-shaped prisms 15 and 16. Said wedges are oppositely turned by being mounted in annular gears 16' rotated from a shaft 17, pinion 17' and reversing gearing 18, shaft 17 being turned from the knob 19. After passing through the wedge-shaped prisms, the line of sight passes through a rotatable erecting prism 20, telescope tube 21, and angularly tiltable prism 22, whence the line of sight emerges laterally toward the target.

The line of sight is represented as rotatable in

azimuth from shaft 23, which turns the assembly on which prism 22 is mounted through pinion 24 and gear 25, while the line of sight is tiltable in elevation by means of a rod 26 pivoted to datum at 27 and 27' through parallel links 26' and movable up and down from segmental gear 28 through link 29. Said gear, in turn, is rocked in elevation from shaft 30. The motion of rod 26 is communicated to prism 22 through an arcuately grooved guide 105 (see Fig. 5) carried by said rod and a ball ended arm extension 104 of the prism holder movable in said guide whereby the up and down movement of rod 26 rocks the prism 22 about a transverse axis 22' to give the line of sight the proper elevation movement relative to the gun for all positions of the prism in azimuth. In Fig. 1B, I have schematically represented an optical sight together with the associated mechanisms for rotating the sight both in elevation and in azimuth and it should be understood that the mechanisms for imparting elevation movements thereto or movements of the prism 22 about the transverse axis 22' are preferably arranged to rotate in azimuth therewith in substantial conformity with well-known practices in this art.

The wedge prisms 15 and 16 are used in finding the slant range of the target. They are circular glass discs which may have their inward faces parallel and their outward faces inclined thereto at a small angle and which can be rotated in opposite directions by the above described gears 17', 18 and knob 19. This arrangement makes the two wedges optically act as one single wedge with the wedge angle variable from zero to a maximum, the resultant wedge angle being proportional to the sine of the angle through which the wedges are relatively turned. Fig. 4A shows the wedges with their inclined outer faces parallel. In this position the bending of a light ray by one wedge is neutralized by a bending in the opposite direction by the other wedge so that the emerging and entering paths are parallel. B represents such a ray, the slight offset which occurs in passing through the double wedge not being shown. The position in Fig. 4A is referred to as the neutral position. When the two wedges are rotated 90° in opposite directions producing a relative rotation of 180°, they are positioned as shown in Fig. 4B. A ray B' is shown bent in the same direction by the two wedges causing a maximum angular deviation from its original path.

The wedges both have a round hole in their center, so that about one-half of all the light rays entering the wedge area will go through the hole without deflection as illustrated by ray A, while the balance of the rays pass through the wedges proper, which results in a refraction of the rays. A person looking through the eyepiece will hence see two images of the target, one direct image (a), Fig. 3, and one deflected image (b). Image (b) will be shifted to one side of the direct image (a) in all cases except where the two wedges are exactly oppositely positioned, which position is said to be their neutral position, and the angular distance through which the image is shifted depends on the rotary position or the angle between the two wedges resulting from a shift from said neutral position and with respect to each other. In the said neutral position, which is reached by turning the wedge adjusting knob 19 until both images merge into one, this angle is zero. By adjusting the wedges, the deflected image of the aircraft can be brought into a position where its wing tip touches that of the direct

image, forming the condition shown at (c) in Fig. 3.

In the triangle thus set up, it is obvious that

$$(1) \tan B = \frac{K}{R}$$

in which B is the angle between the direct and refracted lines of sight, R is the slant range, and K is the wing spread. For the condition illustrated in Fig. 3 with the target directly ahead, K is equal to the distance between the centers of the two images. Since K is known from the type of bomber being attacked, and since B is known from the setting of the wedges, the slant range can thus be obtained, being

$$R = \frac{K}{\tan B}$$

or, for very small angles,

$$(2) R = \frac{K}{B}$$

The angle B is moreover proportional to the sine of the angle through which the wedges are relatively turned, or

$$(3) B = \sin A \times C$$

where C is a constant and A is the angle through which the wedges are relatively turned. Hence we may write

$$(4) R = \frac{K}{\sin A \times C}$$

This condition of course only holds true where the target is directly ahead. In case it is not directly ahead, the wing spread will be foreshortened, which may be taken into account by introducing the angle the line of sight makes with the fore and aft line of the craft (A_z), so that the equation may be written:

$$(5) R = \frac{K \times \cos A_z}{\sin A \times C}$$

The above solution for range is strictly true only when the attacking plane flies a course parallel to that of the target. However, since the departure from parallel courses when it occurs is normally small and the corresponding variation of $\cos A_z$ still smaller, the error in range which affects only a correction factor is neglected in view of the more complicated mechanism required for an exact solution under all conditions. In my sight I prefer to solve equation 5 in its logarithmic form, which may be written:

$$(6) \log R = \log K + \log \cos A_z - \log (\sin A \times C)$$

Log K is set in by turning knob 31 until the logarithmic dial 32 shows the correct value for the wing spread K. Turning said knob also rotates a cam pin 34 threaded through a rack bar 33 and also spring pressed against a cam 35. The position of bar 33 is therefore the algebraic sum of the lift of pin 34 and the rotation of knob 31. Log $\cos A_z$ is the lift of said cam pin 34 governed from the cam 35 on the shaft of gear 24. Therefore the total motion of rack bar 33 represents $\log K + \log \cos A_z$.

Log $(\sin A \times C)$ is the lift value of the cam 36, which is turned from the shaft 37 governing the position of the two wedge prisms through gears 31. The cam pin 38 carries rack teeth which, through pinion 39, rotate one arm of a differential 40. The second arm is rotated from rack 33 through pinion 41 and shaft 41'. The third arm of said differential therefore, through gears 42, rotates a logarithmic range dial 43 in accord-

ance with the aforesaid Equation 6. Therefore the motion of the dial 43 is proportional to $\log R$ and this range may be set into the machine either through power follow-up mechanism or from a handle 44 which turns the dial 45 to match dial 43.

If desired, an extra dial 46 together with knob 47 may be provided for operating in conjunction with the dial 32 for compensating for changes in muzzle velocity of the gun. Variations in muzzle velocity are taken care of by introducing a correction in range by turning the knob 47, thereby shifting the reference line 46' for dial 32.

As explained above, the control handle 1 enables the operator to control the gun positions in azimuth and elevation, but I prefer to provide in addition thereto means for setting in, through variable speed drives, continuous azimuth and elevation movements at adjustable rates. This is accomplished by means of two variable speed drives 48 and 49, the driving discs of which are continuously driven from constant speed motor 50. The elevation variable speed drive 48 is shown as adjusted from the elevation handwheel 51, which turns the central arm of a differential 52. The second arm of said differential is connected through gearing 53 to shaft 54, which radially positions the ball carriage 55 of said drive through bevel pinion 56 and rack and pinion 57. The driven element 58 of said variable speed drive turns the shaft 6 through worm drive 59 which has a slip friction connection 60 with said shaft. It also turns the third arm of the differential 52 through gearing 61. The friction imposed by ball carriage 55 is less than the friction imposed by shaft 6 so that due to the slippage at 60, a forced rotation of handwheel 51 displaces ball carriage 55 without rotating shaft 6.

Similarly, the azimuth handwheel 51' controls the position of the roller carriage 55' of the variable speed drive 49 and drives the shaft 2 through slip friction connection 60'. The slip friction connections are provided so that the control of the gun from the main handle 1 is not interfered with by the automatic rate drives.

When the rate handwheels are in use, the operator turns them to the desired speed and lets go. While the operator is turning the handwheels, the friction at friction couplings 60 and 60' which is greater than that due to ball carriages 55 and 55' holds one shaft of differentials 52 and 52' thereby imparting rotation to shafts 54 and 54' and moving the ball carriages away from their central positions distances proportional to the rates at which the handwheels are turning. When the operator lets go, owing to the back drive from the driven elements 53 and 58' and to the frictional loads imposed on the differentials 52 and 52' by the friction brakes 62 and 62' (Fig. 1A), connected through gearing 63 and 63' to shafts 54 and 54', the handwheels will keep on turning at the imparted rate and any change of speed imparted to these handwheels by the operator will be automatically kept up since rollers 58 and 58' will be rotated at rates proportional to the distances carriages 55 and 55' are moved away from their central positions and the motion of said rollers will be transmitted through differentials 52 and 52' to the handwheels. Also, if the operator stops either handwheel from turning, it will remain at the standstill position. Therefore, these handwheels may also be used as vernier controls to effect small changes of the position of handle 1.

The linear rate of continuous rotation of the handwheels 51 or 51' is represented by the radial distance of the ball carriage 55 from the center of its driving disc, and this rate is transmitted to and made use of in the computer through the shafts 54 and 54'. The azimuth and elevation rates of change of target position (or approximately the corresponding rates of change of gun position) in the present system are considered to be directly proportional to the prediction angles in these two dimensions since range is constant and time of flight is closely proportional to range. Such rates, as representative of prediction angles, are algebraically added to the gun position values through differentials 64 and 64', as received from the repeat-back shafts 9 and 10 from the guns, and the summation of each transmitted to shafts 65 and 65'.

For positioning the line of sight, I therefore employ two factors in both azimuth and elevation (1) the position of the gun as received from shafts 9 and 10; (2) the value of the rate deflections from the rate drive shafts 54 and 54'; and in addition, I employ a third factor (3) the wind corrections as obtained from the computer.

For obtaining the wind deflections in an airplane, the direction of the wind, which is taken to be wholly due to the relative motion of the plane and air, is, of course, always dead ahead and in a horizontal plane and the velocity thereof is the indicated air speed. I resolve the wind velocity into two components in the horizontal plane, (1) across the line of fire and (2) along the horizontal component of the line of fire, i. e., a horizontal component in the vertical plane of the line of fire, which are hereinafter referred to as cross wind T and head wind S. The resolution is preferably accomplished by a resolving mechanism as shown diagrammatically at R in Fig. 1A and shown in perspective skeleton form in Fig. 2. Said mechanism comprises a worm wheel disc 70 turned from a worm 71 which, in turn, is turned through the train or gun azimuth angle from the shaft 9. The air speed, as indicated by the pointer 72 of the air speed meter 100, is matched by the handle 73 and is set into the machine through a differential 74 and shaft 75 which turns shaft 76 by means of shaft 75' to position the rack bar 77 proportionally to the air speed. The plate 77' on which said bar is mounted is movable in guide 103 secured to the face of the disc 70 and rotating therewith. Plate 77' has a hole engaged by a pin 78 on slider 79. The other side of the differential 74 is connected to the shaft 9 to remove the effect of turning of disc 70 in azimuth upon the radical position of the rack bar 77. The slider 79 is mounted for transverse movement in a lateral slideway in the vertically movable T-shaped member 80, through which extends an elongated pinion 81. Rack teeth 82 on the rear of the slider 79 mesh with the said pinion 81 to rotate the shaft 83 thereof. Up and down movement of the member 80 is transmitted by means of rack teeth 85 formed on the rear thereof to a pinion 84 meshing therewith, the pinion being mounted on and secured to rotate with the shaft 86. Hence it will be apparent that the horizontal wind velocity introduced from shaft 76 is resolved into two components S and T (see Figs. 1A and 2), S being transmitted to the shaft 83 of the pinion 81 and T being transmitted to the shaft 86 of the pinion 84, their components being

also functions of the azimuth angle A_z through which worm wheel 70 is turned.

The resolved wind components are each introduced into a pair of three-dimensional cams, by which deflections in azimuth and elevation due to wind are obtained. The head wind shaft 83 is shown as axially positioning a cam 87 through the pinion and rack bar 88 for the factor S. Said cam is positioned rotationally from elongated pinion 89 turned from shaft 10', driven from the elevation repeat-back shaft 10 in accordance with a function of the angle of elevation, i. e. quadrant elevation. Cam 87 is therefore positioned in two dimensions—from quadrant elevation and head wind velocity S, respectively. The lift of the pin thereon, representing a functional combination of quadrant elevation and head wind, axially positions the second cam 90 of the pair 87, 90, said cam being positioned in rotation from the rotation of the shaft 44' turned from the slant range knob 44. The lift of the pin 94 thereon is therefore a function of head wind, slant range and quadrant elevation and represents the wind correction in elevation. It is fed into the differential 92, the other side of which is driven from the elevation repeat-back shaft 10 plus the rate correction introduced through differential 64 operating shaft 65. The second differential 92' is for the purpose of introducing an elevation spot correction from the handle 93.

Similarly, the cross wind T positions rotationally the cam 94 through shaft 86 and bevel gears 86', which cam in turn is positioned axially from the lift of the pin 95 on the second three-dimensional cam 96 of the pair 94, 96. The cam 96 is positioned rotationally from the same pinion 89 which rotates the cam 87 or, in other words, is positioned rotationally from the quadrant elevation shaft 10'. Said cam, in turn, is positioned axially from the same shaft 44' that rotates the cam 90 through gearing 97 and rack and pinion 98, and hence is positioned axially from the slant range. The lift of pin 95 is hence a function of the two variables elevation and range.

The cam 94 is so laid out that the lift of the pin 94' represents a combination of a function of the variable cross wind T with certain functions of elevation and range. The relationships between elevation and wind correction and between range and wind correction are obtained from ballistic tables computed from actual firing tests. The lift therefore represents the wind correction in azimuth or the azimuth deflection which is first fed through the differential 99, where the azimuth spot correction from handle 100' is introduced, and thence into differential 101, where the azimuth rate correction is introduced from the shaft 65' and differential 64'. Finally the sight is positioned in azimuth from the center arm of the differential 101 through the shaft 23, while it is positioned in elevation from the shaft 30, driven from the center arm of the differential 92.

The final effect of introducing the above deflections into the sight is to cause a deviation of the line of sight from the position it would have had with all deflections at zero. It therefore now points to the point to which the projectile would speed in case of firing, and since this point is not coincident with the position of the target, repositioning of the line of sight is necessary. This is accomplished by moving the gun, which action in turn moves the sight back

onto the target. This changes the deflections superimposed upon the direct connection between gun and sight. However, as the gunner is not conscious of this fact and cannot judge the movement of the gun but only that of his reticle, he will move his control handle until the reticle is on the target. As all the deflections are generated simultaneously with the moving of the gun, there is no time delay or lag in the whole train of deflection generation and the gun can be fired immediately the reticle is on the target.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. Thus, many features of my invention are not only applicable to the above described method of indirect positioning of the line of sight starting from the line of fire, but also to the direct method of positioning the line of fire from the line of sight, in which case the connections from the repeat-back shafts to the sight are omitted.

Having described my invention, what I claim and desire to secure by Letters Patent is:

1. In apparatus for applying a windage correction to the aiming angle of an airplane mounted gun during substantially level flight of the plane, means positioned in accordance with the azimuth angle of the gun relative to a normally horizontal axis of the plane, means for obtaining a measure of the airspeed of the plane as representing relative wind velocity effective in deflecting a projectile fired from the gun, means receiving said azimuth angle and wind velocity from said first two means and supplying as a function of said two quantities a measure of the horizontal component of wind velocity across the line of fire, means positioned in accordance with gun elevation angle, means providing a measure of target range, and means receiving said wind component, gun elevation and target range from said several means and actuating wind correction means for altering the azimuth aiming angle of the gun in accordance with a function of said three received quantities.
2. In apparatus for applying a windage correction to the aiming angle of an airplane mounted gun during substantially level flight of the plane, means positioned in accordance with the azimuth angle of the gun relative to a normally horizontal axis of the plane, means for obtaining a measure of the airspeed of the plane as representing relative wind velocity effective in deflecting a projectile fired from the gun, means receiving azimuth angle and wind velocity from said first two means and supplying a measure of the horizontal component of wind velocity along the line of fire, means positioned in accordance with gun elevation angle, means providing a measure of target range, and means receiving said horizontal component of wind velocity, gun elevation and target range from said several means and actuating wind correction means to effect automatically an offset between the line of sight and gun in elevation which compensates for the joint effect of said last three received quantities.
3. Apparatus for compensating for the effect of wind on a shell fired from an airplane mounted gun comprising means for determining a line of sight to a target, air speed means, resolving means actuated thereby and by the gun for ob-

taining a measure of component airspeed in a direction perpendicular to the vertical plane of the gun axis, means providing a measure of target range, a mechanism actuated by and in accordance with the elevation angle of the gun in said plane and said measures of component wind and range, for computing a windage correction to the azimuth aiming angle of the gun, and means automatically correcting the azimuth aiming angle of the gun relative to the line of sight in accordance with said windage correction.

4. An inter-plane fire control device for an airplane mounted gun comprising a sight having members determining a line of sight, means controllable at the sight for simultaneously positioning the gun and line of sight in azimuth and in elevation, means furnishing measures of the air-speed of the firing craft and target range, a computing device including means controlled by and in accordance with gun position for setting azimuth and elevation angles, and means for setting airspeed and range in accordance with the respective measures of said two quantities, said device further including means for deriving from said airspeed and azimuth settings components of effective wind across and along the line of fire and for computing from said components respectively, each in combination with said set elevation angle and range, wind correction angles in azimuth and elevation, and means automatically offsetting the gun and line of sight in said two dimensions in accordance with said angles.

5. In aerial gun fire apparatus for inter-plane fire during substantially level flight of the firing plane, a gun mounted on the firing plane for rotation in azimuth and elevation, a sight including members determining a line of sight independently positionable in said two dimensions for tracking a target, means manually controllable at the sight for simultaneously positioning the gun and line of sight in said two dimensions, a correction computing mechanism comprising wind resolving means receiving airspeed as determined by an airspeed meter and deriving therefrom settings of horizontal wind components across and along the line of fire, including means for supplying to said resolving means azimuth angle of the gun relative to a normally horizontal axis of the craft, means for setting range and gun elevation in said mechanism, said mechanism being adapted to compute from the quantities set therein, deflection angles proportional to the effect of wind in azimuth and elevation, said azimuth deflection angle being computed as a joint function of cross wind, range and gun elevation, and said elevation deflection angle being computed as a joint function of head wind along the line of fire, range and gun elevation, and means for offsetting the line of sight relative to the axis of the gun in accordance with said computed angles, whereby the gunner in keeping the line of sight on the target simultaneously corrects the aiming of the gun for windage.

6. Aerial fire control apparatus for directing inter-plane gun fire during substantially level flight of the firing plane comprising, in combination on the firing plane, a gun mounted for rotation in azimuth and elevation, a sight having optical members determining a line of sight independently positionable in said two dimensions, means manually controllable at the sight for simultaneously positioning said gun and line of sight in said two dimensions, means for obtaining a measure of airspeed, means positionable in accordance with gun azimuth for deriving from airspeed measures of the components thereof

along and across the line of fire, a computing mechanism, means for setting said airspeed components and range in said mechanism, and means controlled by the gun in accordance with the posi-

- 5 tion thereof for setting elevation angle in said mechanism, the said mechanism computing from the set quantities deflection angles in azimuth and elevation proportional to the effect of wind in said two dimensions, means for measuring
10 rates of gun movement in azimuth and elevation, means for combining said measured rates as representing prediction angles with said wind deflections respectively and means automatically operated by said combining means producing offsets between the sight and gun in said two dimensions in accordance with said combined corrections.

15 7. In an inter-plane fire control device for an airplane mounted gun, a sight having members determining a line of sight, means controllable at the sight for simultaneously positioning the gun and line of sight in azimuth and in elevation, means furnishing a measure of the air-speed of the gun carrying, firing craft, a computing device including means controlled by and in accordance with gun position for setting azimuth and elevation angles, means for setting airspeed, said device further including means for deriving from said azimuth and air-speed settings components of effective wind across and along the line of fire and for computing from said components respectively, each in combination with elevation angle, wind correction angles in azimuth and elevation, and
30 means automatically offsetting the gun and line of sight in said two dimensions in accordance with said computed angles.

35 8. In an inter-plane fire control device for an airplane mounted gun, a sight having members determining a line of sight, means controllable at the sight for simultaneously positioning the gun and line of sight in azimuth and in elevation, means furnishing a measure of the air-speed of the gun carrying, firing craft, a computing device including means controlled by and in accordance with the position of the gun for setting azimuth and elevation angles, and means for setting wind in accordance with measured airspeed, said device further including means
40 for deriving from said azimuth and wind settings a component of wind across the line of fire and for computing a wind correction angle in azimuth as a function of said cross wind and elevation angle, and means automatically offsetting the gun and line of sight in accordance with said computed angle.

45 9. In an inter-plane fire control device for an airplane mounted gun, a sight having members determining a line of sight, means controllable at the sight for simultaneously positioning the gun and line of sight in azimuth and elevation, means furnishing a measure of the airspeed of the gun carrying, firing craft, a computing device having means controlled by and in accordance with gun position for setting azimuth and elevation angles, and means for setting wind in accordance with measured airspeed, said mechanism further including means for deriving from said azimuth and wind settings a head wind
50 component along the line of fire and for computing a wind correction angle in elevation as a function of said head wind and said set elevation angle, and means automatically offsetting the gun and line of sight in accordance with said computed angle.

55 75

10. In fire control apparatus for use with a gun mounted on an aircraft for movements in azimuth and elevation and with a gun sight, resolving means including means settable according to the air speed of the aircraft and means movable in proportion to angular displacements of said gun in azimuth to provide an output proportional to a component of said air speed along the longitudinal axis of the gun, a pair of three-dimensional cams arranged for series operation having follower means responsive to the lift of one of said cams for imparting movement in one dimension to the second of said cams, means for moving the second of said cams in another dimension according to a measure of range, the output of said resolving means being applied to move said one cam in one dimension, and means connected to move said one cam in another dimension in proportion to angular displacements of said gun in elevation, said cams being so constructed and arranged that the lift of said second cam will impart movement to a follower according to the elevation angular deflection of a projectile due to the air speed of the aircraft.

11. In fire control apparatus for use with a gun mounted on an aircraft for movements in azimuth and elevation and with a gun sight, resolving means including means settable according to the air speed of the aircraft and means movable in proportion to angular displacements of said gun in azimuth to provide an output proportional to a component of said air speed across the longitudinal axis of the gun, a pair of three-dimensional cams arranged for series operation having follower means responsive to the lift of one of said cams for imparting movement in one dimension to the second of said cams, the output of said resolving means being applied to move said second cam in another dimension, means for moving said one cam in one dimension according to a measure of range, and means for moving said one cam in another dimension in proportion to angular displacements of said gun in elevation, said cams being so constructed and arranged that the lift of said second cam will impart movement to a follower representing the azimuth angular deflection of a projectile due to the air speed of the aircraft.

12. In fire control apparatus for use with a gun mounted on an aircraft for movements in azimuth and elevation and with a gun sight, resolving means including means settable according to the air speed of the aircraft and means movable in proportion to angular displacements of said gun in azimuth to provide an output proportional to a component of said air speed along the longitudinal axis of the gun, a pair of computing devices each having a pair of input members and a single output member, the output member of one of said devices being connected to actuate one input member of the other device, means for actuating the other input member of said other device according to a measure of range, the output of said resolving means being applied to actuate one input member of said one device, and means for actuating the other input member of said one device in proportion to angular displacements of said gun in elevation, said computing devices being so constructed and arranged that the output member of said other device will be displaced according to the elevation angular deflection of a projectile due to the air speed of the aircraft.

13. In fire control apparatus for use with a

gun mounted on an aircraft for movements in azimuth and elevation and with a gun sight, resolving means including means settable according to the air speed of the aircraft and means movable in proportion to angular displacements of said gun in azimuth to provide an output proportional to a component of said air speed across the longitudinal axis of the gun, a pair of computing devices each having a pair of input members and a single output member, the output member of one of said devices being connected to actuate one input member of the other device, the output of said resolving means being applied to actuate the other input member of said other device, means for actuating one input member of said one device according to a measure of range, and means for actuating the other input member of said one device in proportion to angular displacements of said gun in elevation, said computing devices being so constructed and arranged that the output member of said one device will be displaced according to the azimuth angular deflection of a projectile due to the air speed of the aircraft.

14. In apparatus for computing the deflection of a projectile due to the air velocity of a gun, the combination with resolving means including means settable according to air velocity and means movable in proportion to angular displacements of said gun in azimuth, said resolving means providing an output proportional to a component of said air velocity, of a first displaceable member, the displacement thereof being controlled by the output of said resolving means, a second displaceable member, means for displacing said second member in proportion to angular displacements of said gun in elevation, and means responsive to the displacements of said first and second members for moving an output element in accordance with the computed angular deflection of a projectile due to the air velocity of said gun.

15. In apparatus for computing the deflection of a projectile fired from a gun mounted for movement in azimuth and elevation on an aircraft, said deflection being due to the air speed of said aircraft, the combination with resolving means including means adapted to be actuated according to the air speed of said aircraft and means movable in proportion to angular displacements of said gun in azimuth relative to said aircraft to provide an output constituting a measure of a component of said air speed, of a displaceable member, means for displacing said member in proportion to angular displacements of said gun in elevation, computing means actuated by the output of said resolving means and by said member, and an output element movable by said computing means, said computing means being so constructed and arranged that said output element is moved an amount constituting a measure of the angular deflection of a projectile due to the air speed of the aircraft and the angular azimuth position of the gun.

16. In apparatus for computing the deflection of a projectile fired from a gun on an aircraft, said deflection being due to the air velocity of said aircraft, the combination with resolving means including means settable according to air velocity of the aircraft and means movable in proportion to angular displacements of said gun in azimuth to provide an output proportional to a component of said air velocity across the longitudinal axis of the gun, of a displaceable member, means for displacing

said member in proportion to angular displacements of said gun in elevation, computing means actuated by the output of said resolving means and by said member, and an output element movable by said computing means, said computing means being so constructed and arranged that said output element is moved an amount constituting a measure of the azimuth angular deflection of a projectile due to the air velocity of the aircraft and the angular azimuth position of the gun.

17. In apparatus for computing the deflection of a projectile fired from a gun on an aircraft, said deflection being due to the air velocity of said aircraft, the combination with resolving means including means settable according to air velocity of the aircraft and means movable in

proportion to angular displacements of said gun in azimuth to provide an output proportional to a component of said air velocity along the longitudinal axis of the gun, of a displaceable member, means for displacing said member in proportion to angular displacements of said gun in elevation, computing means actuated by the output of said resolving means and by said member, and an output element movable by said computing means, said computing means being so constructed and arranged that said output element is moved an amount constituting a measure of the elevation angular deflection of a projectile due to the air velocity of the aircraft and the angular azimuth position of the gun.

EARL W. CHAFEE.
